UNITED STATES PATENT OFFICE

2,605,986

PAINTBRUSH HOLDER

Gustav O. Schulz, Portland, Oreg.

Application October 18, 1948, Serial No. 55,051

1 Claim. (Cl. 248—113)

1

The present invention relates to a paint brush holder adapted to secure one or more paint brushes pivotally and releasably to the rim of a paint bucket.

In the painting trade, it is customary for the painter to use two or more brushes of different size. He may use a large one, for example, for the major portion of the work and a smaller one for the trim. This practice presents the problem of providing a suitable depository for the idle brush while its mate is being used. Customarily the painter meets this problem by placing the idle brush in his pocket or on some convenient support such as the top of the paint bucket, which is untidy and affords an opportunity for the paint to dry on the brush. Alternatively, he may allow it to remain in the bucket. This is disadvantageous in that it places the weight of the brush on the bristles and bends them and, in addition, may smear the handle of the brush with paint.

Other problems encountered in the painting trade and now met by expedients which are not altogether satisfactory are: that of providing a support for brushes between painting operations, when it is desirable to immerse the brush in a thinner or solvent mixture to clean it and prevent it from drying out; that of providing a wiping surface on which a freshly dipped paint brush carrying excess paint may be wiped to remove the excess thereof; and that of providing a brush holder for attachment to a paint bucket and consisting of one or more brush holding units which will not interfere with each other in use.

It, therefore, is a primary object of the present invention to provide a paint brush holder which may be attached to the ordinary paint bucket and which may be used to support one or more paint brushes with the brush portion immersed in the fluid contents of the bucket but suspended above the bottom thereof, thus preventing the brush from drying out and the bristles from bending.

It is another object of the present invention to provide a paint brush holder which is universal in its application, being adaptable to use on paint buckets provided with inwardly extending lips, as those in which paint customarily is sold, as well as on the lipless buckets to which the professional painter likes to transfer his paint.

Still another object of the present invention is the provision of a paint brush holder which may be employed to hold a plurality of brushes in a

2

single container, the individual units of the holder being pivotally mounted to enable swinging the brushes out of the operating area, thereby leaving a free space for immersing in the contents of the bucket the brush which is being used.

It is still a further object of the present invention to provide a paint brush holder which serves the dual functions of holding the idle brush and of providing a wiping surface on which the brush being used by the painter may be wiped to remove excess paint without spilling it or running it over the edge of the bucket.

It is another object of the present invention to provide a brush holder which may be locked in position on the edge of an ordinary paint bucket so that it cannot be knocked or jarred loose, as upon accidental contact with the paint brush.

Still another object of the present invention is the provision of a paint brush holder which may serve the functions of holding the idle paint brushes with the brush portions suspended in the paint during the painting operation, and in an appropriate solvent or brush cleaner after the painting operation has been completed.

Still a further object of the present invention is the provision of a paint brush holder comprising a plurality of holding units and adapted to hold in a paint bucket a plurality of paint brushes being interchangeably used, the holding unit for the brush in use being rotatable to a position in which it does not interfere with the brush dipping operation.

It is still a further object of the present invention to provide a paint brush holder which is of simple, strong construction and inexpensively fabricated from readily available parts.

It is still another object of the present invention to provide a device for holding several paint brushes in suspension in a container for paint in such a manner that they can be swung to one side out of the way to facilitate the attachment and detachment of the brushes.

Still another object of the present invention is to provide a paint brush holder for one or more brushes that can easily and quickly be attached to or detached from a paint bucket.

The manner in which the foregoing and other objects of the present invention are accomplished will be apparent from the following specification and claim, considered together with the accompanying drawings, wherein like numerals identify like parts and wherein:

Figure 1 is a side elevation, partly broken away, of a paint bucket having an inwardly extending

lip, with the paint brush holder of the invention mounted thereon;

Figure 2 is a fragmentary plan view of the paint bucket of Figure 1, further illustrating the manner of attachment of the paint brush holder of the invention thereto, and its manner of use.

It will be apparent from the drawings that the presently described paint brush holder broadly comprises a pair of bars adapted to clamp on the inwardly extending rim of a paint bucket, one or more brush holding spring clips, and means for pivotally attaching the spring clip or clips to the bars. The lower bar 10 is adapted to lie within the paint bucket 11 beneath the inwardly extending projection or lip 12. The ends of the bar preferably are curved to conform to the curvature of the side wall of the bucket and, if desired, may be bent upwardly to engage the inner groove 12a of the lip. It is perforated at spaced intervals, as at each end and in the central portion, the perforations 13 preferably being substantially square to accommodate the head of a carriage bolt.

The upper bar 14 is shaped and proportioned substantially the same as the lower bar 10 and is adapted to lie on the upper surface of the lip 12. It also may be curved to conform to the curvature of the side wall of the bucket and may have its ends turned downwardly to engage the outer groove 12b of the lip 12 and anchor it in place. It is provided with a plurality of preferably round perforations 15 at spaced intervals, as one at each end and one in the middle, these perforations being opposite and in substantial alignment with the perforations in the lower bar when the two bars are in position on the rim of the bucket. When interconnected by means of the two carriage bolts 16, 16 provided with wing nuts 17, 17, or by a single bolt inserted through the center pair of perforations the bars thus provide a means for clamping to the paint bucket one or more brush holding units. These may be attached to the bars by independent means, although preferably they are thus attached by means of the bolts used to hold the bars together.

The brush holding unit may comprise a spring clip made up of two opposed elongated members or fingers 18, 18 interconnected by means of a volute spring 19, the ends of which are attached to the fingers, as by being bent and placed in a slot therein. In order to attach the spring clip to the bars, the bolt 16 may be inserted through the central portion of the volute spring 19. Then when the wing nut is drawn tight, the lower surface of the spring will bear against the upper surface of the upper bar, while its upper surface will bear against the wing nut 17. In this manner, there is afforded a convenient means for clamping the bars to the rim of the bucket while contemporaneously pivotally mounting the spring clips thereon. The latter then may be used to hold a paint brush 20 immersed at a desired depth in the fluid contents 21 of the container.

When using the brush holder, paint brushes (a large one and a small one for example) may be placed one in each of the spring clips and held immersed to a desired depth in the fluid contents of the bucket. This may comprise a suitable solvent or cleaner, if the brushes are not in active use, or paint or other coating composition when the brushes are being used. In the latter case, the brush to be used may be removed from its

respective spring clip which then may be swung outwardly to the dotted position indicated in Figure 2 with its longitudinal axis substantially parallel to the longitudinal axis of the bar. This leaves substantially the entire opening of the bucket unobstructed so that its contents may be used without interference.

When the use of the first brush is completed, its spring clip holder may be rotated back over the opening of the bucket and the brush placed in the clip, with the brush end immersed in the fluid but out of contact with the bottom of the bucket, thereby preventing bending of the bristles. A number of brushes may be supported and used in this manner, one being stationed at each end of the bar in the usual case, but one or more also being placed at spaced intervals thereon if such is desired.

The bars on which the spring clips are mounted thus serve a four-fold function. In the first place, they serve to clamp the spring clip holders to the inwardly projecting rim of the paint bucket. In the second place, they serve as a support for pivotally mounting the spring clip holders above the opening of the paint bucket. In the third place, they serve a spacing function, enabling positioning of the brush holding units, i. e. the spring clips members, at predetermined and suitable stations along the length of the bar. Finally, the lower bar serves as a wiping bar against which the freshly dipped brush bearing its coat of paint or other coating fluid may be wiped to remove the excess fluid, which falls into the bucket.

Having now described my invention in preferred embodiments, what I claim as new and desire to protect by Letters Patent is:

A paint brush holder comprising an upper perforated bar adapted to lie on the upper side of the lip of a paint bucket, a lower perforated bar adapted to lie on the under side of the lip the bars spanning the opening across the top of the bucket and, the perforations in the upper and lower bars being in substantial alignment with each other, bolts disposed through opposite ones of said perforations, and spring clip members adapted to hold a paint brush and comprising two opposed elongated members interconnected by means of a volute spring the opposite ends of which are attached one to each of the elongated members, one of the spring clip members being placed on each of said bolts with the bolt penetrating the central portion of the volute spring and secured by means of a nut, thereby clamping the upper and lower bars to the lip of the bucket and pivotally mounting the brush-holding spring clip members thereon.

GUSTAV O. SCHULZ.
